UNITED STATES PATENT OFFICE

2,360,763

MANUFACTURE OF FOOTWEAR AND
PARTS THEREFOR

Ervin L. Crandell, Wellesley, Mass., assignor to
Compo Shoe Machinery Corporation, Boston,
Mass., a corporation of Delaware

Application April 10, 1941, Serial No. 387,823

2 Claims. (Cl. 36—12)

This invention relates to the manufacture of footwear, and more particularly to a form of manufacture wherein shoes, or certain parts thereof, are heated by the action of a high frequency electrical field to activate heat responsive materials in the shoe construction, such as thermoplastic bonding adhesives.

General objects of the invention are to provide shoe constructions and shoemaking methods wherein an electrically conductive material such as metallic foil or mesh is incorporated as a permanent component of the shoe construction in such a manner as conveniently to enable its use as an electrode employed in setting up a heating field.

More particularly, objects of the invention are to provide shoe parts adapted to be permanently incorporated in a shoe at or near portions thereof which are to be thermally treated by the heating action of an energized electric field, wherein such parts include a ply of electrically conductive material capable of being arranged in that portion of the finished shoe which is to be thermally treated.

Further object of the invention are to provide a cement sole attaching construction and method wherein a thermoplastic adhesive is placed between the outsole and the lasted upper and is subjected to the heating effect of an electrostatic field set up between electrodes, one or more of which is located beneath the outsole, and another of which forms a component part of the shoe construction, such as an insole or an upper.

Other objects of the invention will in part be obvious and will in part appear hereinafter.

The invention accordingly comprises the several steps and the relation of one or more of such steps with respect to each of the others, and the articles possessing the features, properties, and the relation of elements, which are exemplified in the following detailed disclosure, and the scope of the invention will be indicated in the claims.

For a fuller understanding of the nature and objects of the invention reference should be had to the following detailed description taken in connection with the accompanying drawings, in which:

Fig. 1 is a perspective view of a partly lasted shoe showing an insole construction embodying features of the invention;

Fig. 2 is a longitudinal vertical section of the lasted shoe constructed in accordance with Fig. 1 showing the outsole attached and diagrammatically indicating the outsole attaching electrode arrangement;

Fig. 3 is a perspective view showing another form of insole embodying features of the invention;

Fig. 4 is a perspective view showing an outsole embodying features of the invention;

Fig. 5 is a transverse vertical sectional view across the forepart of a shoe having a special upper embodying features of the invention and showing a fragmentary portion of an electrode equipped sole pressing pad associated therewith; and

Fig. 6 is a partial plan view of the shoe structure shown in Fig. 5, the outsole being removed.

The present invention generally contemplates using a high frequency source of inductive heating such as that described in the patent to E. C. Pitman, No. 2,087,480, issued July 20, 1937, and a thermoplastic or thermosetting adhesive or plastic which is heated on or between plies of other materials by the action of the high frequency energized field.

The Pitman patent discloses that when attaching outsoles to shoes, this field may be set up between an electrode on the last bottom and one on the sole pressing pad of a sole affixing press, which embraces the shoe bottom including the thermoplastic sole bonding area between them. In factories where the lasts have no metal bottoms, or where, for some reason, such bottoms cannot readily be employed for electrode purposes, it is necessary in such an arrangement to provide a special electrode on the last bottom, of the kind shown, for example, in the Smith Patent No. 2,240,867.

The present invention contemplates avoiding the trouble and expense of refitting lasts in this manner by incorporating an inexpensive conductive electrode ply in or on at least one portion of the shoe part itself at a point adjacent the thermoplastic together with means for connecting such insole electrode in a high frequency circuit.

Referring particularly to the drawings, and first to Figs. 1 and 2, there is shown a shoe lasted on a last 10 which may be of conventional construction except that the usual metal jack pin thimble 11 may have an electrically conductive pin 12 extending from the bottom thereof downwardly to the bottom of the last where its lower end is exposed for contact with the adjacent portion of an insole there located. Also, the usual tack clinching metal plate at the heel seat of such last designated 13 is preferably cut away as indicated at 14 to avoid electrical contact with 55 the conductor 12. The shank and forepart por-

tions of the last bottom need have no metal plating nor like electrode construction in view of the incorporation of such parts in other portions of the lasted shoe in the manner about to be described.

The shoe comprises an upper 15 which may have a lining 16 and is adapted to be lasted in any suitable manner to an insole 17. In the form illustrated the upper is cement overlasted against the underface of the insole, although stitching or even metal staple lasting may be employed if desired.

The insole 17 is of laminated construction comprising an upper or foot-side ply 18 and a lower or sole-side ply 19 having between them a cemented-in sheet or electrode 20 of electrically conductive material such as fine copper mesh, aluminum, or silver foil, or the like. Where a foil rather than a mesh is used, such foil may preferably be perforated or cut away from those areas in which an electric heating field is not particularly desired in order to afford a direct cemented bond between the insole plies 18 and 19 which are made of relatively non-conductive material such as leather or fibre composition. The foot side ply 18 has a slot 21 near the heel breast line through which a rearwardly extending tongue or connector 22 is led for exposure on the inner face of the insole next to the last bottom and beneath the conductor 12.

In making a shoe such insole is located on the last bottom with the electrode tongue 22 in contact with the conductor 12 and the upper is lasted thereto. The lasting allowances of the upper and of an outsole 23 are then roughed and coated with a thermoplastic adhesive, preferably one of the thermoplastic types described in the mentioned Pitman Patent 2,087,480, such as vinyl resin in a toluol solution. The adhesive may be allowed to dry through evaporation of the solvent ready for subsequent activation by a high frequency electrostatic field. This field is applied by placing the shoe and outsole with, if needed, a suitable filler 24 therebetween and with their cemented faces in contact; in a suitable shoe press, not shown, having a flexible electrode associated with its sole engaging pad and underlying at least the shank and forepart areas of the shoe sole. Such an electrode 25 is diagrammatically represented beneath the outsole in Fig. 2, being shown opposed to the metallic foil or mesh electrode 20 forming a component part of the insole. The shoe press pad electrode is shown connected to the power side of any suitable type of high frequency generator, while the last jack pin thimble is connected with the ground side of such a circuit, thus connecting the insole electrode 18 through the conductor 12 with the circuit. If desired, the insole electrode may be connected with the power side of the high frequency generator circuit and the shoe press pad electrode grounded, or the opposed electrodes may be connected with opposite sides of a push-pull oscillator circuit, all as is well understood in the art of generating high frequency current. While the shoe is held in the press under suitable sole affixing pressure, an electrostatic field is set up between the insole and pad electrodes, preferably at the frequency of 20 to 25 megacycles over a suitable period of time and at a suitable power value, although these features, including the frequency employed, will depend on the individual shoe construction, type of adhesive, etc., and are unnecessary to an understanding of the use of the particular electrode construction herein claimed.

On certain types of footwear such as sandals, open toe and/or heel shoes, the insole is usually bound along the marginal edge with a decorative binding such as leather, oil cloth, or like materials, and I have found that such decorative binding when lined with a metallic foil or mesh forms an excellent electrode for attaching the outsole by means of a thermoplastic adhesive as previously described. Accordingly, this form of insole construction is shown in Fig. 3 and comprises an insole 30 to which a decorative binding 31 is stitched and/or cemented to its marginal edge. The binding material has a metallic foil or other conductive material 32 attached to the under side thereof and another piece of conductive material in the form of a tab 33 is attached to the heel end of the insole on the foot side, and the binding 31 is arranged to overlap same so as to form a continuous metallic electrode.

The heel tab serves to form an electrical connection with the last thimble extension 12 (Figs. 1 and 2) and can be removed from the finished shoe if desired.

Thus the form of insole described above is well adapted to serve as an electrode without the addition of an electrode on the last bottom of the shoe, and the strip of metallic foil in connection with the decorative binding around the insole serves to stiffen same and can be speedily and cheaply manufactured.

In Fig. 4 another form of my invention is shown which comprises a laminated outsole unit adapted for adhesive attachment to a lasted upper. It is especially useful when a heavy or thick outsole is desired and has the advantage that it can be made from relatively cheap materials, as the wearing ply can be cut from a thin hide and a skiving or split can be utilized for the attaching face or foot side ply.

Referring to Fig. 4, the outsole unit consists of a wearing ply 40 and an upper ply 41 which can be skived, roughed, and cemented in the usual manner for attachment to a shoe upper. Cemented between these leather plies is a sheet 45 of metallic foil or mesh 42 which is provided with a projecting lip 43 which serves as a convenient connection to one side of a suitable high frequency generator. In attaching this outsole unit to a shoe bottom, the metallic foil 42 serves as a lower electrode and eliminates the necessity of an electrode on the pad of the sole attaching press. The upper electrode may be of the type previously described as being part of the insole, or it may be of the form shown in Figs. 5 and 6, wherein it is a strip attached to the shoe upper as hereinafter described.

An arrangement whereby a shoe upper is provided with an electrode which forms a part of the shoe structure is shown in Fig. 5. This structure comprises a shoe upper 45 and its lining 46. Around the lasting allowance is sandwiched a strip of metallic foil or the like 47 which is secured by the stitches 48 or by any suitable adhesive. The entire upper is shown lasted over a conventional insole 49, its lasting allowance having been roughed, cemented, and the filler piece 50 and outsole 52 in place ready for the sole affixing operation.

The electrode sandwiched between the upper and lining is provided with an extension 51 as shown in Fig. 6 to serve as a connection to the high frequency electrical source. This extension 51 can readily be formed by allowing the foil to continue beyond the heel breast line and then allowing it to protrude out between the lining

and upper and simply bending same over, substantially as shown.

In attaching a sole 52 to the shoe structure described, it is only necessary to connect one side of the high frequency source to the electrode extension 51, and then seat the shoe and outsole on a suitable shoe press pad electrode diagrammatically represented in Fig. 5.

Since certain changes in carrying out the above process, and certain modifications in the articles which embody the invention may be made without departing from its scope, it is intended that all matter contained in the above description or shown in the accompanying drawings shall be interpreted as illustrative and not in a limiting sense.

Having described my invention, what I claim as new and desire to secure by Letters Patent, is:

1. A laminated insole having upper and lower plies and an interior ply of metallic material, said upper ply of said insole having a slot formed therein at its heel end, through which a portion of said metallic ply passes.
2. In a shoe, an inner sole having upper and lower plies, a metallic ply between said plies, the upper of said plies having a slot formed therein at its heel end, and a portion on said metallic ply extending through said slot and above said upper ply and adapted to engage electric conducting means extending through a last and contacting said portion.

ERVIN L. CRANDELL.
